WATER HEATING SYSTEM

Clark M. Osterheld, Stoughton, Wis., assignor to
 McGraw Electric Company, Elgin, Ill., a corpora-
 tion of Delaware

Application June 14, 1941, Serial No. 398,094

4 Claims. (Cl. 219—39)

My invention relates to electric temperature control systems and particularly to water heating control systems.

An object of my invention is to provide a relatively simple all-day water heating system.

Another object of my invention is to provide a water heating control system embodying thermal means subject to tank water temperature at a predetermined point or height of the tank to vary the amount of electric energy translated into heat for the water in the tank.

Other objects of my invention will either be apparent from a description of my invention as embodied in several modifications or will be pointed out in the course of such description and set forth in the appended claims.

In the drawing:

Figure 1 is a schematic diagram of connections embodying my invention shown as applied to an ordinary domestic hot water tank, which is shown generally only, and,

Fig. 2 is a view similar to Fig. 1 showing a modified system of control.

Since the system embodying my invention is particularly applicable to and useful in the control of electric heaters used on ordinary domestic hot water tanks, I have elected to show, schematically only, a hot water tank 11 which is to be understood as being provided with a cold water inlet pipe, preferably at the bottom of the tank, and with a hot water outlet pipe at the top of the tank. The tank may also be provided with the usual layer of heat insulating material and with an outer protective casing for such material. However, since my invention has nothing to do with these details, I have shown the tank generally only.

Referring to Fig. 1, an electric heater comprises two sections 13 and 15 and I may make the resistance of these two sections the same or I may make the resistance of section 13 greater than that of section 15 so that when section 15 is energized separately, the amount of electrical energy translated into heat in section 15 will be greater than if section 13 were energized alone. I prefer to apply these two sections of the heater to the tank near the lower end thereof, as shown in Fig. 1 of the drawing.

I provide a lower main thermal heater control switch 17 here shown as embodying a tubular member 19 so secured to the wall of tank 11 as to extend into the tank in a fluid-tight manner. An expansion rod 21 is positioned within the tubular member 19 and extends outwardly beyond the outer surface of the wall of tank 11 engaging a

5 contact or switch arm 23. This contact arm is adapted to engage with or be disengaged from a fixed contact member 25. When tubular member 19 is subject to cold water, switch arm 23 will be in engagement with fixed contact member 25 but if tubular member 19 is surrounded by and subject to hot water, the expanded rod 21 will have moved the switch arm 23 out of engagement with fixed contact member 25 to thereby interrupt a circuit controlled by this switch.

I provide an auxiliary thermal switch 27 which is preferably located at an intermediate point or height of the tank 11 and for illustrative purposes it may be positioned at about one-half of the height of the tank or even at about two-thirds of the height of the tank from the bottom. Switch 27 includes a tubular contact member 29 secured to the wall of the tank in a fluid-tight manner to be positioned within the tank and has located therein an expansion rod 31 adapted to move a contact or switch arm 33. The movable end of arm 33 is adapted to engage either one of two fixed contact members 35 and 37, it being understood that the design, construction and adjustment of the thermal switch 27 is such that the free end of arm 33 is in engagement with either contact member 35 or with contact member 37, but has no intermediate position. I may use any of the present types of two-operative position switches now on the market to obtain this result but have not shown any details thereof since they do not form any part of my present invention.

I provide two supply circuit conductors 39 and 41, supply circuit conductor 39 being connected to the pivotally mounted end of switch arm 33. Fixed contact member 35 is connected by a conductor 43 with one terminal of each of the heater sections 13 and 15. The other end of heater section 13 is connected by a conductor 45 with the fixed pivotal end of switch arm 23. Contact member 25 is connected by a conductor 47 with fixed contact member 37. The other terminal of heater section 15 is connected by a conductor 49 with the other supply circuit conductor 41.

Let it be assumed that the tank 11 has just been filled with cold water and that the supply circuit conductors 39 and 41 are connected to suitable supply circuit of electric energy. The two thermal switches 17 and 27 will be in substantially the position shown in Fig. 1 of the drawing, e. g., switch arm 23 will be in engagement with fixed contact 25 and switch arm 33 will be in engagement with fixed contact 35. An energizing circuit through the heater will

therefore be established substantially as follows: From supply circuit conductor 39 through engaged switch arm 33 and contact 35, through conductor 43 and through heater section 15 to and through conductor 49 to the other supply circuit conductor 41. An amount of electrical energy will therefore be translated into heat depending upon the resistance of heater section 15 and since this heater section alone is connected in circuit, in this diagram of connections, it may be considered that a relatively large amount of electrical energy is translated into heat causing the temperature of the water in the tank to increase at a relatively rapid rate.

Let it now be assumed that the amount of hot water in the tank has increased, because of the flow of current for some time through heater section 15 and attendant heating of the water, to such an extent that tubular member 29 of the upper or auxiliary thermal switch is surrounded by hot water. When this occurs the expanded rod 31 will cause movement of switch arm 33 out of engagement with fixed contact 35 and into engagement with fixed contact 37 whereby a new circuit through the heater is provided, substantially as follows: From supply circuit conductor 39 to and through engaged switch arm 33 and contact 37, through conductor 47 to and through engaged contact 25 and switch arm 23, through conductor 45, through heater sections 13 and 15 connected in series circuit with each other and from there through conductor 49 to the other supply circuit conductor 41. It will therefore be evident that when a certain fractional part of the amount of water in the tank has been heated to a given temperature, the upper or auxiliary thermal switch will cause a change-over in the heating circuit whereby the two sections of the electric tank heater are connected in series circuit with each other whereby the amount of electrical energy translated into heat is greatly reduced.

It is therefore evident that when the tank, at any time, contains a relatively small amount of hot water, which may be considered to be less than that required for normal household needs and purposes, the amount of electrical energy translated into heat is relatively large but as soon as an amount of water in the tank sufficient for normal household purposes has been heated, the amount of electrical energy translated into heat and applied to the water in the tank is greatly reduced.

Referring now to Fig. 2 of the drawing, I have there illustrated a modified system embodying my invention. I have shown a two-section heater comprising sections 49 and 51, both sections being located near the lower end of the tank 11. For purposes of illustration I have shown a main lower thermal switch 53 as including a flexible bimetal bar 55 having one end thereof mounted on suitable electric and heat conducting means subject to the temperature of the water in the lower part of the tank and adapted to engage with and be disengaged from a fixed contact member 57. This main thermal heater control switch need not be of the two-operative position type since it is merely required to open the circuit when substantially all of the water in the tank is hot and I have shown a bimetal switch to illustrate that such a type of switch may be used.

I provide an upper thermally actuatable heater control switch 59 which includes a tubular member 61 substantially the same as tubular member

29 and located at an intermediate height of the tank which may be either at one-half height or at two-thirds height from the bottom of the tank. An expansion rod or bar 63 is adapted to pivotally move a contact or switch arm 65 in accordance with the temperature of the water to which the tubular member 61 is subjected. An outer fixed contact member 67 may be engaged by switch arm 65 when the tubular member 61 is subject to hot water. I provide two inner fixed contact members 69 and 71 spaced apart from each other and adapted to be engaged by contact or switch arm 65 when tubular member 61 is subject to cold water. Switch 59 is designed, constructed and adjusted so that arm 65 is in engagement with either contact 67 or with contacts 69 and 71.

Supply circuit conductor 39 is connected to the pivotally fixed end of contact arm 65. Contact members 67 and 69 are connected together by a conductor 73 which at the same time connects them with the fixed end of bimetal bar 55 of the lower main thermal heater control switch. Contact member 71 is connected by a conductor 75 with one terminal of heater section 51. The other terminal of heater section 51 is connected to one terminal of heater section 49 which two terminals are connected by a conductor 77 with supply circuit conductor 41.

Let it be assumed that tank 11 as shown in Fig. 2 has just been filled with cold water and that supply circuit conductors 39 and 41 are connected to a suitable source of supply of electric energy. Bimetal bar 55 will be in engagement with fixed contact member 57 and contact arm 65 will be in engagement with fixed contact members 69 and 71. This establishes an energizing circuit through the two-section heater substantially as follows: From supply circuit conductor 39 to and through engaged contact arm 65 and fixed contact member 69, through conductor 73 to and through the engaged members of the lower main thermal switch 53 and from fixed contact 71 through conductor 75 through heater section 51, and through heater section 49, through conductor 77 to the other supply circuit conductor 41. It is evident that the two heater sections are connected in parallel circuit relation with each other. It is therefore evident that when the upper thermal heater control switch 59 is subject to cold water, current will flow through both sections of the heater in parallel whereby a relatively large amount of electrical energy will be translated into heat causing a relatively rapid heating up of the water in the tank 11 and its collection at the upper part of the tank, in a manner now well known in the art.

When the amount of hot water heated by current flowing from the two sections of the electric heater has increased to such an extent that the upper auxiliary thermal switch 59 is subject to hot water, contact arm 65 will be moved out of engagement with fixed contact members 69 and 71 and into engagement with fixed contact member 67 whereby another energizing circuit through the heater is established substantially as follows: From supply circuit conductor 39 to and through engaged contact arm 65 and contact 67, through conductor 73 to and through bimetal bar 55 and engaged contact member 57, through a conductor 79 to and through heater section 49 and from there through conductor 77 to the other supply circuit conductor 41. Therefore, when the upper part of the tank is filled with hot water to such an extent that the upper auxiliary thermal switch 59 is surrounded by hot

water, it will be effective to establish a new energizing circuit through only one of the sections of the electric heater. Let it be assumed that the ohmic resistances of heater sections 49 and 51 are the same. Then it is evident that when only heater section 49 is energized as just above described, the amount of energy translated into heat will be only one-half of that which is translated into heat when both heater sections are energized in parallel circuit with each other, as is the case when the thermal heater control switch 59 is subject to cold water.

It will be noted that the lower thermal heater control switch 17 or 53 is in circuit and in complete control when the tank is filled with hot water and causes complete deenergization of the heater as soon as the tank is full of hot water. In case of withdrawal of hot water, in small quantities, the lower thermal switch will reclose and cause reenergization of the heater at low watt input.

The two systems shown in the drawing and hereinbefore described will therefore be effective to translate a greater amount of electrical energy into heat when the tank contains no or only a small amount of hot water and it is, of course, to be understood, as has already been hereinbefore stated, that this small amount of hot water is that which would be required to meet the normal demands or calls for hot water in the course of the daylight hours.

While I have not shown any means for recording the amount of energy used during the daytime as distinguished from that used during so-called off-peak hours, such means may be provided but are not shown since they constitute no part of my present invention.

Various other modifications may be made in the system embodying my invention without departing from the spirit and scope thereof and I therefore desire that all such modifications as are clearly covered by the appended claims shall be included as a part of my invention.

I claim as my invention:

1. A control system for a hot water tank having a plural-section electric heater applied thereto near the lower end of the tank and adapted to heat water in only the lower end of the tank, comprising a switching means having two operative positions, a thermal element subject to tank water temperature at a point substantially one-half of the height of the tank and adapted to move said switching means from one to the other of its operative positions in accordance with its ambient temperature, electric connections between the heater sections and the switching means to cause the generation of a greater amount of heat by said heater when the upper half of the tank is filled with cold water than when the upper half of the tank is filled with hot water and a second thermally-operative switch subject to tank water temperature at the lower end of the tank for deenergizing said heater when substantially all of the water in the tank is hot.

2. A control system for a hot water tank having a two-section electric heater applied thereto near the bottom end of the tank and adapted to heat water in only the lower end of the tank, said system comprising a thermally-actuable switch having two operative positions and subject to tank water temperature near the upper end of the tank, electric connections between the switch and the heater sections to bias the thermally-actuable switch into a first operative position to cause the generation of a predetermined amount of heat in the heater when the upper part of the tank is filled with cold water and to move the thermally-actuable switch into its second operative position to cause the generation of a smaller amount of heat in the heater when the upper part of the tank is filled with hot water.

3. A control system for a domestic hot water tank having a greater height than diameter and having a plural-section electric heater applied thereto near the lower end of the tank adapted to heat water in only the lower end of the tank, comprising a switching means having two operative positions, a thermal element subject to tank water temperature in the upper part of the tank, electric connections between the switching means and the electric heater, the thermal element holding the switching means in one of its operative positions to cause the generation of a predetermined amount of heat when subject to cold water and causing the switching means to move into its other operative position to effect the generation of a lesser amount of heat when the thermal element is subject to hot water, a second switching means comprising a thermal element subject to tank water temperature in the lower end of the tank and normally holding the second switching means in heater energizing position when subject to cold water and effective to move the second switching means to heater deenergizing position when the water in the lower end of the tank is hot.

4. A control system for a domestic hot water tank having a greater height than diameter and having a plural-section electric heater applied thereto near the lower end of the tank adapted to heat water in only the lower end of the tank, comprising a switching means having two operative positions, a thermal element subject to tank water temperature in the upper part of the tank, electric connections between the switching means and the electric heater, the thermal element holding the switching means in one of its operative positions to energize one only of said heater sections when the thermal element is subject to cold water and causing the switching means to move into its other operative position to energize both said heater sections in series circuit with each other when the thermal element is subject to hot water.

CLARK M. OSTERHELD.
